(57) **CLAIM**

The ornamental design for a surveillance camera assembly, as shown and described.

DESCRIPTION

FIG. 1 is a first perspective view of a surveillance camera assembly embodying the present invention.

FIG. 2 is a second perspective view of a surveillance camera assembly of FIG. 1.

FIG. 3 is a third perspective view of a surveillance camera assembly of FIG. 1.

FIG. 4 is a front view of the surveillance camera assembly of FIG. 1.

FIG. 5 is a rear view of the surveillance camera assembly of FIG. 1.

FIG. 6 is a first side view of the surveillance camera assembly of FIG. 1.

FIG. 7 is a second side view of the surveillance camera assembly of FIG. 1.

FIG. 8 is a top view of the surveillance camera assembly of FIG. 1; and,

FIG. 9 is a bottom view of the surveillance camera assembly of FIG. 1.

The present application is directed to the shape and contour of the designs illustrated in the drawings. The elements shown in broken lines form no part of the claimed design and are included for the purpose of showing the environment of the claimed design.

1 Claim, 9 Drawing Sheets
